UNITED STATES PATENT OFFICE

THOMAS W. VARLEY AND WILLIAM C. NEIN, OF NEW YORK, N. Y.

TRAIN CONTROL

Application filed January 19, 1928. Serial No. 247,792.

This invention relates to the control of trains traveling along a right of way, as for instance railway trains traveling along a rail track, it being understood that by "control" of 5 trains is meant either the operation of a signal whereby the train operator is caused to control his train accordingly, or the automatic control of the train without the intervention of the operator is effected.

10 One object of the invention is to provide apparatus such that the desired objects may be obtained when the control between the vehicle and right of way is effected through the instrumentality of thermionic vacuum 15 tubes, the desired control being effected by change in character of the operation of the tube or tubes.

In carrying out our invention we preferably make use of a thermionic vacuum tube of 20 the audion type, and effect the desired control by causing a change in the character of operation of the tube by changing the oscillatory character of the tube as by changing it from oscillating to non-oscillating or from one 25 character of oscillation to another character of oscillation such as by changing from one frequency of oscillation to another frequency of oscillation. A control between the vehicle and right of way may be thus effected by 30 means of oscillations of such high frequencies as to come within the class known as radio frequencies.

This has many advantages among which 35 may be mentioned the permissible flexibility of relative positioning of the relatively moving parts upon the track and vehicle respectively, and the lack of necessity of having the vehicle parts run close to those on the right of way whereby danger of the relatively moving parts coming together and being broken, and on the other hand too wide separations of 40 those parts causing failure of operation, is avoided.

A further object of the invention, is consistently with the aforesaid character of control, to provide means whereby the normal condition of the system is to produce a danger condition either as to signal or automatic control of the train so that the effect of a controlling influence is necessary to maintain clear

conditions or conditions under which the vehicle may proceed.

A further object of the invention is to effect control of a vehicle as indicated in combination with a speed control means. 55

A further object of the invention is to provide means in a system of the character as indicated whereby the operator may at will obviate the effect on the vehicle of automatic devices otherwise acting upon the vehicle. 60

A further object of the invention is to provide in a system of the character as indicated means for effecting control as to "danger," "caution" and "clear" conditions of the right of way. 65

A further object of the invention is to provide a system of the character as indicated whereby the desired control is effected by reason of the cooperative action of a plurality of thermionic vacuum tubes. 70

Other and ancillary objects of the invention will appear hereinafter.

In the accompanying drawings which illustrate the invention—

Fig. 1 is a diagrammatic view of a vehicle equipment for a system of control embodying the invention; 75

Fig. 2 is a diagrammatic view of a railway track and equipment adapted to cooperate with the vehicle equipment of Fig. 1; 80

Fig. 3 is a diagrammatic view showing another form of vehicle and track equipment; 85

Fig. 4 is a diagrammatic view of another form of vehicle and track equipment; 85

Fig. 5 is a diagrammatic view showing another form of vehicle equipment; and 85

Fig. 6 is a diagrammatic view of a track and equipment adapted for cooperation with the vehicle apparatus of Fig. 5. 90

Fig. 7 is a view showing in side elevation the speed controlled disk and the time controlled disk and the manner of cooperation of contacts thereon.

Referring to the drawings and first to Figures 1 and 2, there is therein illustrated a system of train control whereby a vehicle or train upon a railway track is controlled by controlling the oscillatory character of thermionic vacuum tubes of the audion type. 95

These tubes are controlled by means of track instruments which are in turn controlled by wayside signals or other means indicative of the condition of the track ahead.

5 The apparatus shown in the figures referred to comprises a "run-down" device which is operated from the running gear of the vehicle so as to run down as the vehicle progresses. Having started to run down at 10 the beginning of a block, if the conditions are "clear" in the next block the "run-down" device will be reset to its initial position at appropriate times without causing any effect upon the progress of the vehicle. If, however, there are "caution" conditions in the 15 next block the "run-down" device will continue its movement, and in cooperation with a speed control device so that the engineer is obliged to keep his train within the prescribed speed limits in order to avoid the application of brakes and the stopping of his train. If at the end of the "caution" block the conditions in the next block ahead have become "clear" the speed control and "run-down" devices will be restored to the initial 20 clear position so that normal conditions are resumed or, if the signal at the end of the "caution" block is at danger the "run-down" device will continue its movement and the 25 brakes will be applied and the vehicle stopped or, if the signal at the end of the "caution" block is another "caution" signal, the "run-down" and "speed control" devices will be returned to the initial "caution" position so 30 that the "caution" conditions of operation will be continued through the second "caution" block.

The "run-down" device and its cooperating speed control device comprises a worm wheel 40 or disk 1 which is driven in the direction of the arrow *a* by means of a worm 2 driven by a flexible shaft 3 from the axle 4 of the vehicle. At appropriate times the worm 2 is lifted out of engagement with its cooperating gear 1 by means of the energization of the magnet 5. Energization of this magnet is controlled by the apparatus in accordance with track conditions as will be hereinafter more fully referred to.

50 The worm wheel 1 has its initial position defined by means of a lug 13 fixed upon it which comes against a spring contact 14 which in turn comes against the stationary stop 15. A spring 16 secured at one end to the worm wheel and at the other to a stationary part 17 tends to return the gear 1 to its initial "clear" position when it has been released from the worm 2. The contact 14 when released from the lug 13 comes into 55 engagement with the contact 18 so that when the gear 1 has left its initial (clear) position these contacts will be closed, and when the gear is in its initial position these contacts will be opened, for a purpose as will be 60 hereinafter referred to.

The brake magnet 6 when deenergized causes the air brakes to be applied by permitting a valve in the air vent pipe 7 to open. Normally this valve is held closed by the energization of the magnet 6 caused by the closing of the circuit of that magnet through the battery 8 and contacts 9 mounted upon but insulated from the worm wheel 1, connection between these contacts being made by a metal segment 10 fixed upon but insulated from the speed control disk 11 which has circumferential ratchet teeth 12, the contacts 9 bearing upon the segment 10. The speed control disk 11, which is rotatably mounted, tends to be turned in the direction of the arrow *b*, (the same direction as the arrow *a*) by means of a spring 19 having one end connected to the stationary member 20 while the other end is connected with the piston 21 of a dash-pot which in turn is connected by a band or cord 22 with the periphery of the speed control disk 11. The speed control disk has its turning measured by lapse of time rather than by distance traveled as in the case of the worm gear disk 1, the rate at which the speed control disk 11 turns being controlled by regulating the dash-pot in a well known manner to allow the piston to move faster or slower under the influence of the spring 19, it being preferable that the dash-pot shall be regulated to permit a relatively fast movement at the fore part of the downward movement of the piston and then slower, the speed curve of the piston preferably simulating the braking curve of the train. The speed control disk is normally held in its initial position, that is, with its stop lug 23 against the stationary stop 24, by means of a dog 25 pivoted on a stationary part and on an axis parallel to the face of the disk 11 and normally held in position to engage the ratchet teeth 12 on the speed control disk, and to be moved out of engagement with the ratchet teeth by means of a camming segment 26 fixed to the worm wheel and which passes under the tail of the dog 25. The speed control disk 11 is limited in its movement in the direction of the arrow *b* by means of a stationary stop 27 which engages the lug 23.

105 Approximately on the same radius as the stationary stop 24 is another stationary stop 28 serving to define the initial "caution" position of the worm wheel 1 as will be hereinafter more particularly referred to.

110 A magnet 29 is normally deenergized under "clear" conditions but is energized under "caution" conditions. When the magnet 29 is deenergized the spring 30 tends to move the tail of a pivoted bracket 31 against the limiting stationary stop 32, at which time the spring contact 33 mounted upon the other arm of the bracket 31 is out of the path of the lug 13. When, however, "caution" conditions exist the magnet 29 attracts the tail 115 120 125 130

of the bracket 31 against the resistance of the spring 30 so that it projects contact 33 into the path of the lug 13 but not quite touching the stop 28. The result is that when the lug 13 has moved past the spring arm 33, and tending to be reset under "caution" conditions it will come against the arm 33 which will be forced against the stop 28 thereby preventing any further backward movement of the worm wheel 1 and also separating the contact 33 from the contact 34, thereby opening the circuit between them for a purpose as will be hereinafter referred to. If the wheel 1 is reset under "clear" conditions the member 33 will not be projected into the path of the lug 13 so that the wheel will be returned to the initial clear position.

The worm wheel 1 also has pivoted upon it a pawl 38 tending to be pressed into engagement with the ratchet teeth 12 on the speed control disk by a spring 36. This pawl has the detent point or nose 35 and the tail 37. The tail 37, during the movement of the worm wheel, engages the inner edge of the stationary segment 40 and so holds the nose 35 of the pawl out of engagement with the ratchet teeth 12 until it reaches the indented or cut away portion 41 after which the ratchet engages the teeth 12.

It will be observed that when the pawl is in engagement with the teeth the worm wheel 1 cannot move in the direction reverse to the arrows without carrying the speed control disk with it, but on the other hand the worm wheel may move in the direction of its arrow independently of the speed control disk.

In order that the "run-down" and speed control devices as just referred to may be caused to operate in conformity with conditions of the track ahead, there are provided upon the vehicle two thermionic vacuum tubes, of the audion type, 42 and 43, each of which comprises a heated element, a grid and a plate as is well understood and conventionally illustrated. The filament or heated element is in each case supplied with current from batteries 44 and 45 in the usual way and the desired control is effected by changes in the value of the current in the plate circuits according to whether the respective tube is in a condition of oscillation or non-oscillation. The oscillatory current is transferred from one tube to another by inductive action between the coils 92 and 93 located on the track, and the corresponding train carried inductors.

With regard to the tube 42 there is in circuit between the plate 46 and the filament 47, a battery 48 and electro-magnet 49 and a variable inductance 50. The grid 57 is connected through a conductor 51 with one terminal 52 of the coil 53, while the other terminal 54 of that coil is connected by a conductor 55 through a variable condenser 56 with the

plate 46. The filament 47 is connected by a conductor 58 with an intermediate tap 59 of the coil 53. Connected across the conductors 51 and 55 is a variable condenser 60. The arrangement and construction is such that when the tube 42 is acting as an oscillator the plate current will be of sufficient strength to attract the armature of the relay 49 and when the tube is non-oscillating the plate-current is reduced so that the armature will be dropped. 70

It will be seen that the armature cooperating with the coil 49 is divided into two parts, one insulated from the other, one of which parts is adapted to engage with the back contact 80, while the other part is adapted to engage with the forward contacts 81 and 82. When, therefore, the armature is dropped it establishes connections from one terminal of the battery 77 through the relay armature, contact 80, conductor 83, relay coil 84 and 85 conductor 85 to the other terminal of the battery 77. The coil 84 being thus energized attracts its armature 86.

The armature 86 being attracted, contacts with the forward contact 87 and thereby 90 closes a circuit through the coil of the relay 88 across the terminals of the battery 77. The relay 88 then picks up its armature 89 and establishes a connection with the forward contact 90 which is connected by the conductor 91 with the contact 82 of the relay 49. When the armature of relay 49 is lifted the contact 82 is connected with the contact 81 and thence circuit is made through the magnet 29 and the magnet 5 to one side of the battery 77; the relay 84 having a holding circuit made through its armature and the contacts 33 and 34, holds its own circuit closed so long as the contacts 33 and 34 are in engagement and thus maintains the circuit of the magnet 88 which maintains the circuit through the magnet 5 which raises the worm 2 and disengages it from the worm wheel 1. 100

It will be seen that the circuit of relay 88 is initially established by the dropping 110 of the armature of the relay 49 whereby the circuit of the coil of the "stick" relay 84 is completed, and this in turn establishes by its armature the circuit of the coil 88. After the relay 49 picks up its armature again the 115 circuit of the coil 84 will be maintained as above stated. Also, the energizing of magnet 49 will establish the circuit through magnets 29 and 5 permitting the worm wheel to be reset. The initial circuit of the coil 88 having been made by the energization of the magnet 84 upon the dropping of the armature of the magnet 49, when that armature is again picked up the circuits of the magnets 88 and 84 will be made through the contacts 33 and 34, and the contacts 86 and 87, the relay 84 acting as a "stick" relay, that is, maintaining its own circuit closed. Relay 84 also maintains the circuit of the relay 88 so that these relays remain closed until the 120 125

circuit is opened at the contacts 33 and 34. The armature of the relay 49 having been again raised, the circuit through the magnets 29 and 5 across the battery 77 is made through the contacts of the relay 88 and contacts 81 and 82 of the relay 49, and obviously the circuit of these magnets 5 and 29 will be broken when the magnets 84 and 88 are de-energized by the separation of the contacts 33 and 34.

Referring now to the vacuum tube 43, it will be seen that the grid 61 is connected by a conductor 62 with one terminal 63 of the coil 64. The plate circuit extends from the plate 65 through a variable reactance 66, one winding 67 of the relay 68 and the battery 69 to the conductor 70 which is connected both with the filament or heated element 71 and with an intermediate tap 72 of the coil 64. Also a circuit may be traced from the plate 65 through the variable condenser 73 and conductor 74 to the other terminal 75 of the coil 64. A variable condenser 76 is connected between the terminals 63 and 72. When the tube 43 is not oscillating the armature of the relay 68 will not be picked up owing to the low value of the plate current. If, however, the tube 43 is oscillating the armature of relay 68 will be picked up owing to the increased value of the plate current and will then close the circuit from one terminal of the battery 77 through the winding 78 of the relay 68 thence, through the armature of the relay, the conductor 79, contacts 18 and 14, and the magnet 5 to the other terminal of the battery 77 so that if the plate current through the winding 67 is reduced by reason of the tube 43 becoming non-oscillating the coil 78 will maintain the armature of the relay 68 lifted. It will be understood that the winding 78 maintains the armature lifted after the contacts 14 and 18 have become closed by the "run-down" device moving slightly from its initial position. When, however, the "run-down" device has been reset to its initial position the contacts 14 and 18 will open, thereby permitting the armature to drop and it cannot be again raised until the tube 43 again becomes oscillatory by reason of certain track conditions as will be referred to later.

Spaced along the trackway are a series of track instruments each comprising two coils 92 and 93, two of the terminals of which are connected together by a conductor 94 to which is connected a conductor including a variable condenser 95. The other terminals of the coils are connected respectively with the conductor 96 and the conductor 97 the latter connection including the variable condenser 98.

Referring particularly to Fig. 2 a railway comprising the lines of rails 200, 201 and having the rails divided into blocks by sections of insulation as 202, 202', and 203, 203' and 204, 204' has moving along it a vehicle

as diagrammatically shown at 205, this vehicle being assumed to be moving from left to right as shown in Fig. 2, as indicated by the pointed front thereof. These sections of insulation divide the railway track into blocks ⁷⁰ c, d, e and f. Adjacent the beginning of each block is a suitable wayside signal which may be of the semaphore type indicated by the pivoted semaphore arms 206, 207 and 208, which semaphores are precisely the same ⁷⁵ and may be operated from the track blocks to indicate conditions of certain portions of the track. Thus the signal 208 indicates the conditions in the block f, the semaphore 207 indicates conditions in the block e and the semaphore 206 indicates conditions in the block d. Located in the trackway at the end of the block c and adjacent the beginning of block d are the two coils 92 and 93 referred to in connection with Fig. 1 as adapted to cooperate with the coils 53 and 64 upon the vehicle.

As will be seen, the conductor 97 is connected with a contact 209, the condenser 95 is connected with a contact 210 and the conductor 96 is connected with a contact 211. The contacts 209, 210 and 211 are adapted to be engaged by the semaphore arm so that the semaphore arm as it turns upon its pivot will at one time connect the contact 209 with the contact 211 (as in the position shown at c) and at another time connect the contact 210 with the contact 211, opening the circuit between the contacts 209 and 211, and at another time will rest upon the unconnected contacts 212 and 213 at which time both of the contacts 209 and 210 will be unconnected.

It will be seen from Fig. 2 that at the end of block d and adjacent the beginning of block e and at the end of block e and adjacent to the beginning of block f are respectively placed coils 92a, 93a and 92b and 93b which are precisely the same in construction as the coils 92 and 93 and adjacent each section is a semaphore wayside signal precisely the same in construction as the signal 206 and that the contacts and connections are the same in arrangement in each case.

Regarding the coils 92b and 93b and the semaphore signal 208, however, it will be seen that there is a vehicle or train in the block ahead and consequently the semaphore arm is in "danger" position and the circuits of both of the coils 92b and 93b are open. The semaphore arm 207 at the end of block d and the beginning of block e is in "caution" position, and it will be seen that the circuit of the coil 93a is open, while the circuit of the coil 92a is closed through the condenser 95a ¹¹⁵ (which is exactly the same in construction as the condenser 95). It will further be seen that in the apparatus at the end of block c and beginning of block d the semaphore is in "clear" position and the coils 92 and 93 ¹²⁰ 93' are closed through the condenser 95a and 95b. The conductors 96 and 97 are connected to the contacts 209 and 210 respectively at the end of block c and beginning of block d. The conductors 96 and 97 are connected to the contacts 212 and 213 respectively at the end of block d and beginning of block e. The conductors 96 and 97 are connected to the contacts 209 and 210 respectively at the end of block e and beginning of block f.

have their circuit closed in series through the condenser 98.

The operation of the apparatus may now be traced as follows.

The apparatus having assumed a "clear" condition at the beginning of block *c* the parts upon the vehicle will be in condition as shown in Fig. 1, the tube 42 being normally oscillating and the tube 43 being normally non-oscillating. As the vehicle proceeds along the track the driving gear will drive the worm wheel 1 in the direction of the arrow *a* and almost simultaneously with the beginning of this driving the contacts 14 and 18 will be closed. The circuit of brake magnet 6 will be closed through the contacts 9 and 10 and the brakes will be held off. The vehicle thus proceeding, the nose 35 of the dog 38 will be held out of engagement with the ratchet teeth 12 by the stationary segment 40 (and the speed disk 11 is held stationary by the dog 25).

It will be observed that the segment 10 upon the speed control disk is of considerable extent so that the worm wheel 1 carrying the contacts 9 may have considerable range of movement without causing the contacts 9 to slide off of the segment 10. Just before the tail 37 of the dog reaches the depression 41, and just before the cam end of the segment 26 enters beneath the tail of the dog 25 to remove its nose from the ratchet teeth, and just before the lug 23 leaves the stop 24, the coils 53 and 64 on the vehicle run over the coils 92 and 93 which, as we have seen, are set for "clear" conditions in the block ahead (*d*), and the adjustments and constants of the connected circuits in the track and on the vehicle are such that not only is the tube 42 maintained oscillatory but the tube 43 has its character changed from non-oscillatory to oscillatory. When the tube 43 becomes oscillatory the armature of the relay 68 is picked up, and is held up by a circuit through the contacts 14 and 18 and the reset magnet 5 and winding 78. The reset magnet being energized the worm 2 is then drawn away from its wheel which is returned to its normal position by the spring 16, with its lug resting against the contact 14 and stop 15. During all of the movement thus far described, both forward and return, of the worm wheel the dog nose 35 has been held out of engagement with the ratchet teeth 12 and the speed control disk 11 has been held stationary by the dog or pawl 25 so that no movement of the speed control disk has taken place. It will also be observed that in assuming its initial position the worm wheel 1 has opened the contacts 14 and 18, thereby deenergizing the relay 68 and permitting its armature to fall so that the apparatus is in the same condition at the beginning of block *d* as it was in block *c*.

The vehicle then proceeding along block *d*

the vehicle coils 63 and 64 will come over the track coils 92a and 93a and it will be observed that the semaphore in this case is at the "caution" position so that the coil 93a will have its circuit open while the coil 92a will have its circuit closed through the condenser 95a. The coil 93a not having its circuit closed, there will be no reflection of the wave in the coil 53 to the coil 64 so that the coil 64 will remain non-oscillating. Connections of the circuit of the coil 92a, however, are such that the tuning and oscillatory character of the circuit of the tube 42 will be destroyed so that the tube 42 will become non-oscillatory. The armature, therefore of the magnet 49 will be dropped closing the initial circuit at the contact 80 for the coil 84 which will cause the armature 86 to lift and close the circuit of the coil 88 whereupon the circuit is made through the contacts 89 and 90, 81 and 82 and the armature 29 and the magnet 5. The magnets 5 and 29 are thus energized and this takes place after the lug 13 has passed the arm 33. The energization of the magnet 29 causes the armature 33 to be thrust into the path of the lug 13 and the energization of the magnet 5 causes the worm wheel 1 to be released from its worm so that wheel 1 will be returned by its spring 16 to a position against the arm 33 and stop 28, namely the initial "caution" position as distinguished from the initial "clear" position which exists when the lug 13 is against the arm 14 and stop 15. At the time this action takes place the dog having the nose 35 will have come into engagement with the ratchet teeth 12 and the holding dog 25 will have been released from its ratchet teeth so that when the lug 13 is against the stop 28 the speed disk 11 will have been reset so that its lug 23 is against the stop 24. It will be observed that the pawl 38 permits the speed disk 11 to rotate clockwise under the influence of spring 16, in being restored to the position illustrated in Fig. 1.

When the lug 13 comes against the spring contact arm 33 it will separate the contacts 33 and 34 thereby breaking the circuit of the relay 84 which will result in the deenergization of the relay 88 and of the reset magnet 5 whereupon the worm 2 will again fall into mesh with the worm wheel 1. This being the condition at the beginning of the block *e*, movement of the train along the block will cause the worm wheel 1 to turn and beginning with its initial "caution" position and the speed control disk 11 will move from its initial position with the lug 23 against the stop 24 under the influence of the spring 19 regulated by means of the dash-pot 21. The speed control disk 11 will move at a predetermined rate, and the rate and the speed of the train will be limited because the engineer will be obliged to so limit the speed of his

70

train that the contacts 9 will not be driven out of engagement with the contact segment 10 before the end of the block. If these contacts separate from the segment 10 the circuit of the brake magnet 6 will be broken and the brakes applied. The engineer is thus limited in his speed within the block *e* so that upon encountering a danger signal for the next block his speed will not be so great that he will be unable to comply with the signal. It will be apparent, however, that in blocks of sufficient length it is only necessary that his speed be limited for a distance at the end of the block equal to the braking distance of the train, and previous to this braking distance a higher speed would do no harm. For this reason the dash-pot 21 is constructed (in a manner as is well understood in the art) so that for a time prior to the necessary braking time the dash-pot will permit a fast movement of its piston and so a relatively fast movement of the speed control disk 11, so that during the first part of the "caution" block the speed control disk 11 may move at a relatively high speed and so permit a relatively high speed of the vehicle without danger of breaking the circuit of the magnet 6. At a time, however, to permit sufficient braking distance at the end of the block in case of a danger signal for the block ahead, the dash-pot 21 is so constructed that its piston slows up and this speed of the dash-pot piston may desirably be made to simulate the braking curve of the train so that the engineer is limited in his speed according to that curve. This permission of higher speed at the beginning of a "caution" block also has the function of permitting the use of the system on blocks of variable lengths. If, for instance, the distance between signals should not be of the normal length provided for in the apparatus as above described the train would run into a section having the "caution" conditions but, the relatively high speed would be permitted during the first part of the block in which these conditions exist as just explained. The high speed of "clear" conditions could be maintained and then the apparatus would be reset to initial "caution" or initial "clear" according to the condition of the block ahead when the track coils for controlling the train for that block are reached. Of course, if there should be danger set for the block ahead the brakes would be applied and the train stopped as will be hereinafter described.

The train or vehicle continuing along the block *e* after the "caution" signal at the beginning of that block as shown in Fig. 2 and above referred to, the vehicle coils 53 and 54 will, near the end of the block, come into cooperative relation with the track coils 92*b* and 93*b*. Since, however, the semaphore 208 is in "danger" position, the circuits of both these track coils will be open so that they will

exert no effect on the oscillatory character of either of the vacuum tubes on the vehicle. No change in the vehicle apparatus will therefore be produced so that as the vehicle enters the block *f* the worm wheel 1 will continue its movement and, unless the train is sooner stopped by the engineer, the speed control disk 11 will reach the limit of its movement 1, (lug 23 against stop 27) and finally the contact 9 will leave the segment 10 and the brakes will be applied. Ordinarily the contact 10 extends downwardly far enough to permit the train to traverse the longest block at a reduced rate of speed. This is controlled by the speed of dashpot 21 and the length of the contact 10. The upper end of contact 10 is sufficiently long to permit the train to stop just inside the caution block and remain there the full time required for stop 23 to contact with stop 27 without opening brake magnet circuit 6.

If the signal at 208 were another "caution" instead of "danger," the vehicle apparatus would be reset to initial "caution" and proceed accordingly into block *f*. If the signal were "clear" the apparatus would be reset to initial "clear" and the vehicle would proceed along the block *f* accordingly.

Referring now to Fig. 3 of the drawings, there is therein shown equipment whereby the progress of a vehicle is automatically controlled in accordance with the conditions of the track ahead by controlling the thermionic vacuum tubes, it being possible, however, for the engineer to obviate the automatic control by taking suitable action.

The vehicle equipment comprises two normally oscillating thermionic vacuum tubes of the audion type 100 and 101, and a coil 102 operatively related to the vacuum tubes so as to affect the magnet 103 for controlling the air brakes, together with suitable relays and other devices to effect the operation as indicated and as will be presently described more in detail. There is also upon the vehicle a resetting or restoring device 104 which may be manipulated by the engineer to avoid automatic operation of the brakes. Mounted in the track or along the right of way and adjacent the beginning of each block so that it may cooperate with the vehicle coil 102 as it passes, is a coil 105 having circuits adapted to be controlled by track conditions as will be hereinafter referred to.

The apparatus shown on the vehicle depends for its operation upon the change in plate current effected by change in the oscillatory character of the vacuum tubes. The vacuum tube 100 has the usual heated element 125 or filament 106, the grid 107, and the plate 108. The filament 106 is heated in the usual way by means of a battery 109. The grid is connected through a variable condenser 110 with one terminal of the coil 102 and also through

a variable reactance 111 with the other terminal of the coil 102.

The plate circuit extends from the filament through the battery 112, the coil of the relay 113 and the variable reactance 114 to the plate 108. Also there is connected between the filament and plate the variable condenser 115 and the inductance coil 116 which is in inductive relation to the coil 111. This tube being normally oscillating the plate current will normally be sufficient to maintain the armature of the relay 113 lifted.

Similarly the tube 101 has the filament 117, energized in the usual way by the battery 118, the grid 119 and the plate 120. The grid is connected through a variable condenser 121 with one terminal of the coil 102 and through the variable reactance 122 with the other terminal of the coil 102. The plate circuit extends from the filament through the battery 123, the coil of the relay 124 and the variable reactance 125 to the plate 120. Also there is connected in series between the plate and the filament a reactance 126 and a variable condenser 127, the reactance 126 being in inductive relation to the reactance 122. The circuits upon the car as just described are so tuned or adjusted that both tubes are normally oscillating, that is, when the vehicle coil 102 is not over or in cooperative relationship with the track coil 105. Normally, therefore, the currents in the coils of the relays 113 and 124 are sufficient to maintain their armatures raised so that the circuit including the magnet 103 and the battery 128 in series is maintained closed while the circuit including the battery 128' and the "caution" signal light 129' is open. The brake magnet 103 is therefore normally energized and maintains the valve in the brake pipe closed so that the brakes are held off. When, however, the train is passing a track instrument or an instrument located on the right of way so that the train coil 102 is brought into cooperative relation with the coil 105, the oscillatory character of the vacuum tubes is changed according to the circuit connections of the coil 105 which connections are controlled in response to the conditions of the track ahead, for instance by the operation of a way side signal.

The vehicle, it will be understood, is traveling upon a track divided into blocks in the usual way and having a coil 105 located adjacent the beginning of each block as shown in Fig. 2. It is also to be understood that there is at the beginning of each block a way-side signal of the semaphore type (also as shown in Fig. 2). Such a signal is indicated at 150 in Fig. 3. The arm of this signal is adapted in the "clear" position to close the contacts 128 and 129, when in "caution" position to close circuit between the contacts 1290 and 130 and to leave the contacts 128, 129 and 130 disconnected when the way-side signal is in the "danger" position. The devices 131

and 132 are variable condensers. It will thus be seen that the constants of the circuits including the coil 105 will be varied according to the position of the way-side signals operated in the usual manner by means of track relays, and when the vehicle has its coil 102 in cooperative relation with the track coil 105 the tuning of the vehicle circuits of the track coil and the oscillatory character of the tubes change accordingly with corresponding results.

With the tubes on the vehicle normally oscillating as before stated, and the brakes consequently held off because of the energization of the track magnet 103, if the coil 102 comes into cooperative relation with the coil 105 when the way-signal controlling it is in "clear" position the coil 105 will be short circuited and the effect on the vehicle circuits will be such that the oscillatory character of the tubes will be maintained, the brakes will be maintained off and the train may proceed as usual.

If, however, the signal is at "caution" the contacts 129 and 130 will be closed so that the condensers 131 and 132 will be connected in parallel across the terminals of the coil 105 so that by their effect upon the coil 102 the vacuum tube 100 will become non-oscillating while the constants in relation to the tube 101 are such that the last mentioned tube continues to scillate. The result is that the plate current of the tube 101 through the coil of the relay 124 is maintained strong enough so that its armature is maintained raised and the brake magnet 103 energized so that the brakes are maintained "off."

The non-oscillation of the tube 100, however, causes its plate current to be reduced so that the coil 113 drops its armature thereby closing the circuit of the "caution" signal lamp 129' through the battery 128' to thus notify the engineer of "caution" conditions. The non-oscillation condition will continue only for the brief interval that the coil 102 is passing over the coil 105 and for that reason the relay 113 is caused to be so slow in picking up its armature that the action of the signal 129' (which may be a lamp, bell, gong or other suitable device) will become effective to notify the engineer. The retarding means for causing the armature to be slow in rising may be a dashpot or means for preventing rapid building up of current in the coil 113 or other well known and suitable means.

If the signal 150 is at "danger", it will close no circuits and the circuit of the track coil 105 will remain closed through the condenser 132 only. When the vehicle coil 102 is in cooperative relation with the track coil 105 under such conditions the tube 101 is rendered non-oscillating whereupon its plate current diminishes to such an extent that the relay 124 drops its armature thereby breaking the circuit of and deenergizing the brake magnet 130.

103 and the brakes will be applied. The engineer is advised in advance of this condition by the "caution signal" 129 and also by observation of the wayside signal, and may 5 avoid the application of the brakes by manipulating the device 104 so as to close the normally open connection between the conductors 123 and 124. This places a shunt about the contacts of relay 124 so that the 10 opening thereof does not open the circuit through the battery and brake magnet, the magnet remains energized and the brakes are held "off". By this means the engineer may 15 avoid the automatic action under a "danger" condition but insures that he must be cognizant of this condition in taking manual action to avoid automatic action to allow the train to proceed and any inattention, resulting in failure to avoid the action, will cause 20 automatic application of the brakes.

Referring to Fig. 4 there is therein shown a vehicle equipment whereby the application or withholding of the application of the brakes of the vehicle is controlled by the controlling of the oscillation of a thermionic vacuum tube of the audion type. In this apparatus a single vacuum tube is shown which is adapted to indicate "clear" and "danger" 25 conditions, the latter of which may be modified in its operation upon the brakes by means of manipulative action of the engineer. The track coil, instead of being controlled by a semaphore as is the preceding illustrations in connection with Figs. 1, 2 and 3, is controlled directly by the usual track relay which as is well known is connected across the track rails across which a battery is connected so that the relay is normally energized but when a train stands on the rails the 30 relay is short circuited and deenergized. The train carried apparatus comprises the thermionic vacuum tube 133 having the heated element or filament 134, the grid 135 and the plate 136. The filament is heated in the 35 usual way by a battery 137. The grid 135 is connected with one terminal of the vehicle coil 138. Through the plate 136 a circuit extends from the variable reactance 140, through the coil of the relay 141 and the battery 142 to an intermediate point of the vehicle coil 138. Also a connection extends from the reactance 140 through the variable 40 condenser 143 to the other terminal of the coil 138. A condenser 139 is connected between the plate and grid circuits as shown. The track coil 144 has connected across its 45 terminals a variable condenser 145 which may be short circuited by the lift of the armature of the track relay 146 which is controlled from the track by the track relay 146 in the usual way.

The tube being normally oscillating, the current in the plate circuit through the relay 141 will be sufficient to maintain the armature raised and the circuit of the brake magnet

147 closed in series with the battery 148 so that the brakes will be held off. If the coil 138 comes into cooperative relation with the track coil 144, if the condition of the track ahead is such ("clear" condition) that the armature of the coil 146 is lifted, the condenser 145 is short circuited and also the circuit of the coil 144 is closed by the short circuit. The tuning of the circuits related to the vacuum tube on the vehicle is not changed and the relay 141 maintains its armature lifted and the brakes are held off so that the train can proceed as usual. If, however, when the coil 135 is in cooperative relation with the coil 144, there are "danger" conditions in the track ahead, the track magnet 146 will be deenergized and drop its armature but the coil 144 will have its circuit closed through the condenser 145 and the coil 144 will react upon the coil 138 to change the constants of the circuits related to the vacuum tube so that it will be rendered non-oscillating. The relay 141 will then drop its armature whereupon the brake controlling magnet 147 will be deenergized permitting the brake valve 30 to open, whereupon the brakes will be applied. The engineer or operator may, however, avoid the application of the brakes by closing a normally open circuit at the hand operated switch 149 which will operate to close a short circuit about the armature contacts of the relay 141 so that when the relay 141 drops its armature the circuit of the brake magnet will still be maintained and the application of the brakes will be prevented. The engineer is thus able by taking action, to prevent the application of the brakes and upon his failure to do so the brakes will be applied under the conditions as indicated.

Referring to Figs. 5 and 6, the vehicle equipment comprises a normally oscillating thermionic vacuum tube 300 having the heated element or filament 301 energized by the usual battery 302, the grid 303 and the plate 304. The vehicle equipment also comprises a normally non-oscillating thermionic vacuum tube 305 having a filament 306 energized by the usual battery 307, a grid 308 and a plate 309. Circuit is made from the plate 304 through the variable reactance 310, the coil of the relay 311 and the battery 312 to the filament 301. Also connection is made from the plate 304 through the variable condenser 313 and the conductor 314 to one terminal of the coil 315. The grid 303 is connected by a conductor 316 with the other terminal of the coil while the filament 301 is connected by the conductor 317 with an intermediate tap of the coil 315. A variable condenser 318 is connected between the conductors 314 and 316 connected to the terminals of the coil 315.

The tube 305 has its plate 309 connected through a variable reactance 319, the coil of the relay 320 and a battery 321 to the filament

306. The plate 309 is also connected through a variable condenser 322 and a conductor 323 with one terminal of the coil 324 and the filament 306 is connected by a conductor 325 with 5 an intermediate tap of said coil. A variable condenser 327 is connected between the conductors 323 and 326. The tube 300 being normally oscillating, the current in its plate circuit through the coil of the relay 311 will 10 normally be sufficient to maintain its armature lifted as shown. On the other hand, the tube 305 being normally non-oscillating, current in its plate circuit through the coil of the relay 320 will normally be insufficient to 15 maintain its armature raised so that it will normally be in dropped position as shown. There is also included in the equipment upon the vehicle a coil 328 which is included in a circuit closed through the coils of the 20 relays 329 and 330 and the battery 331. Normally the battery 331 causes sufficient current to flow in the circuit so that the armatures of both the relays 329 and 330 are lifted. The coil 328 is adapted, as the vehicle 25 moves along the right of way, to come within the inductive influence of magnets in the track way so that relative movement of the track magnets and vehicle coil as the vehicle passes along the right of way will cause a 30 single cycle of electro-motive force to be induced in the circuit of the coil 328. One-half of said cycle is opposed to the electro-motive force of the battery 331 so that it tends to cut down the current flowing in 35 the coils of the relays 329 and 330. If this cutting down of current is sufficient the armatures of either or both of the relays 329 and 330 will be dropped. The parts are so proportioned and arranged that the armature 40 of the relay 330 will drop at any speed of the vehicle above 30 miles an hour and the armature of the relay 329 will also be dropped at vehicle speed above 10 miles an hour. Normally the armatures of the two 45 relays 329 and 330 in series close the circuit of the coil of the relay 332 through the battery 333 so that the coil of the relay 332 is normally energized. It therefore normally holds its armature lifted and thereby closes 50 the circuit of the brake magnet 334 through the battery 335 and this brake magnet being normally energized maintains the brake valve closed so that the brakes on the vehicle are held off. The brake magnet 334 is made 55 sluggish in its operation by causing a short circuited coil to be inductively related to its battery energized winding or in other suitable ways. It will thus be seen that when either or both of the relays 329 and 330 drop 60 their armature or armatures, the brake magnet will be deenergized and the brakes applied. Whenever the current in the plate circuit of the tube 300 through the magnet of the relay 65 311, by reason of change in the oscillatory
- character of the tube, becomes so small that the armature of the relay is no longer sustained, the armature will drop and close a circuit through the coil of the relay 336 and the battery 337. The relay 336 will then 70 pick up its armature which will close circuit from the battery 337 through the winding of the relay 338. The armature of the relay 336 also closes the circuit of its own winding, through the armature of the relay 338 and across the battery 337 independently of the armature of the relay 311. The effect of the tube 300 causing its plate current to be reduced and the armature of the relay 311 to be dropped, is only momentary 75 so that after a very short interval that armature is picked up again. The relay 338 is sluggish in picking up by reason of having a short circuited winding in proximity to its battery connected winding or said relay may be made sluggish in any of the other suitable and well known ways known to the art. When therefore the more quickly acting relay 311 has picked up its armature, but the more sluggish relay 338 has not picked up 80 its armature, circuit through one of the windings of the relay 339 and the battery 337 will be completed through the armatures of the relays 336, 338 and 311. When sufficient time has elapsed for the relay 338 to pick 85 up its armature, the circuit through the winding of the relay 336 and the winding of the relay 339 as just referred to, will be broken and also the circuit of the winding of the relay 338 will be broken. 90
- When the oscillatory character of the tube 305 is so changed from normal to cause a sufficient increase in its plate current through the relay 320 to cause the relay armature to be picked up, circuit will be closed through the coil of the relay 340 and the battery 341. The relay 340 being thus energized will pick 95 up its armature. This will cause the circuit of the stick relay 340 to be made through its own armature and the armature of the relay 342, battery 341, magnet 340 and left contact of relay 340 independently of the contacts to the relay 320. The relay 342 is made sluggish in operation as has been described in connection with relay 338. The armature 100 of the relay 340 will therefore remain stationary after the momentary operation of the relay 320 and for a period as determined by the sluggish operation of the relay 342. The lifted armature of the relay 340 also 105 closes the circuit of the coil of the relay 342 in series with its own armature and the armature of the relay 340 across the battery 341. Also with the armature of the relay 340 lifted and that of the relay 342 not yet raised 110 on account of the sluggish action of the relay, circuit will be made through another winding on the relay 339 across the battery 341 by means of the conductors 343 and 344, circuit being made at this time across the bat- 115
- 120
- 125
- 130

battery 341 through the winding of the relay 345 by means of the conductors 344 and 346. The two windings of the relay 339 are cumulative so that when either or both are energized as described the armature of the relay will be lifted.

Referring to Fig. 6, there is there shown a railway track divided into blocks *g*, *h*, *i* and *k*, track coils 347 and 348, 347a and 348a 10 and 347b and 348b arranged in pairs at the beginning of each block, a vehicle or train 340 and semaphore signals 351, 352 and 353 all as described in connection with Fig. 2. Fig. 6 has however in addition a permanent 15 magnet in the track, one following each pair of coils at the beginning of each block as for instance the permanent magnets 349, 351 and 352.

The operation of the apparatus may now 20 be indicated as follows: if the train is proceeding along the block *g* under "clear" conditions the coils 315 and 324 on the vehicle will come into cooperative relation with the track coils 347 and 348. The semaphore 25 350 being in "clear" position these track coils will be connected in series through the variable condenser 353 whereby, the tuning and constants being suitable as is well understood in the art, the tube 305 will have its 30 oscillatory condition changed so that its plate current through the relay 320 will cause that relay to pick up and the sluggish relay 342 will cause the condition established to persist for an appreciable length of time. 35 The tube 300 still retaining its oscillatory condition so that its relay 311 retains its armature, the windings of the relays 339 and 345 will be energized from the battery 341 only (not from 337). The armatures of both 40 these relays will therefore be lifted and mechanically hold the armature of the relays 329 and 330 in closed position so that the brakes are held off and the train may proceed as usual regardless of any impulse which may 45 be induced in the coil 328 by the track magnet 349 when that coil later comes into inductive relation to that magnet.

The train now proceeding under "clear" 50 conditions along the block *h*, adjacent the end of that block the vehicle coils 315 and 324 will come into cooperative relation respectively with the track coils 347a and 348a. Here however, the signal 351 is set to indicate "caution" conditions in the block ahead, and 55 causes the circuit of coil 348a to be open and the circuit of the coil 347a to be "closed" through the variable condenser 354. The constants and tuning are then such that the 60 oscillatory character of the tube 305 is not changed from normal while that of the tube 300 is so changed as to reduce its plate current so that the relay 311 drops its armature. It will be seen from the foregoing 65 description that the conditions then are that one winding only of the relay 339 will be

energized, the relay 345 being not energized. The armature of the relay 345 therefore, will not be picked up while that of the relay 339 will be picked up and will lock the relay 329 closed, the armature of relay 330 being free to fall if released by its winding. If thereafter the coil 328 passes the permanent magnet 351 at a speed as great as 30 miles an hour (the speed at which the coil will have induced in it an impulse sufficient to reduce the current in the relay 330 to or below the dropping point of its armature) the armature of relay 330 will break the circuit to the brake magnet and application of the brakes will ensue. If the speed is kept within the limit 70 the train may proceed.

The train now proceeding under "caution" 75 conditions along the block *i*, the coils 315 and 324 will, near the end of the block, come respectively into cooperative relation with the track coils 347b and 348b. The semaphore here is set to "danger" and the circuits of both the coils 347b and 348b are such that as the vehicle passes no change will be caused in the oscillatory character of either of the 80 vacuum tubes. Neither of the armatures of the relays 339 nor 345 will be lifted and neither of the armatures of the relays 329 and 330 will be locked and if the train runs into the "danger" block so that the vehicle 85 coil 328 passes the permanent magnet at a speed greater than ten miles per hour (the limit of speed without dropping the armature of relay 329) the circuit of the brake magnet will be opened and the brakes applied. The brake magnet is made slow acting or sluggish as above referred to so that 90 if the vehicle should be running in the opposite direction from that indicated, the brakes would not be applied by reason of the impulse received from the permanent magnet in the track. Also such action could be prevented by passing over properly energized coils acting upon the vacuum tubes. 95 In this way the vacuum tubes can exercise 100 their control of the train even though it may be moving in the direction the reverse of that indicated in the drawings.

While the invention has been illustrated 105 in what are considered its best applications, it may have other embodiments without departing from its spirit and is not therefore limited to the structures shown in the drawings.

What we claim is:

1. The combination with a vehicle adapted 110 to travel along a right of way, of means on said vehicle for affecting the progress thereof, means biased by the progress of said vehicle to affect the aforesaid means, means including a thermionic vacuum tube becoming an oscillator under suitable circuit conditions for controlling said biased means, and an instrument on said right of way and 115 connections on said vehicle adapted to con- 120

125 130

trol the character of said tube and thereby control said biased means.

2. The combination with a vehicle adapted to travel along a right of way, of means on said vehicle for affecting the progress thereof, means biased by the progress of said vehicle to affect the aforesaid means, means including a thermionic vacuum tube becoming an oscillator under suitable circuit conditions for controlling said biased means and an instrument and connections on said vehicle adapted to control the oscillatory character of said tube to thereby control said biased means.

15 3. The combination with a vehicle adapted to travel along a right of way, of means on said vehicle for affecting the progress thereof, means biased by the progress of said vehicle to affect the aforesaid means, means including a thermionic vacuum tube becoming an oscillator under suitable circuit conditions for controlling said biased means and an instrument controlled by conditions of the right of way ahead and connections on said vehicle adapted to control the character of said tube to thereby control said biased means.

4. The combination with a vehicle adapted to travel along a right of way, of means on said vehicle for affecting the progress thereof, means biased by the progress of said vehicle to affect the aforesaid means, means including a thermionic vacuum tube becoming an oscillator under suitable circuit conditions for controlling said biased means, an instrument controlled by conditions of the right of way ahead and connections on said vehicle adapted to control the oscillatory character of said tube to thereby control said biased means.

30 5. The combination with a vehicle adapted to travel along a right of way, of means on said vehicle for affecting the progress thereof, means biased by the progress of the vehicle to affect the aforesaid means, speed control means cooperating with said biased means, means including a thermionic vacuum tube becoming an oscillator under suitable circuit conditions for controlling said biased means, an instrument on said right of way and connections on said vehicle adapted to control the character of said tube and thereby control said biased means.

35 6. The combination with a vehicle adapted to travel along a right of way, of means on said vehicle for affecting the progress thereof, means biased by the progress of the vehicle to affect the aforesaid means, controlling means involving time as an element cooperating with said biased means, means including a thermionic vacuum tube becoming an oscillator under suitable circuit conditions for controlling said biased means, an instrument on said right of way and connections on said vehicle adapted to control the character of

said tube and thereby control said biased means.

7. The combination with a vehicle adapted to travel along a right of way, of means on said vehicle for affecting the progress thereof, means controlled by the distance traversed by said vehicle along the right of way, an actuator therefor, a disconnecting device for said actuator, means for restoring the controlled means, a plurality of vacuum tubes, one of which governs the extent to which said restoring means shall act effecting operation of the disconnecting device, another of said tubes controlling the first tube as to its effecting the operation of the disconnecting device.

8. The combination with a vehicle adapted to travel along a right of way, of means on said vehicle for affecting the progress thereof, means controlled by the distance traversed by said vehicle along the right of way, time controlled means associated therewith and governed thereby, an actuator therefor, a disconnecting device for said actuator, means for restoring the controlled means, a plurality of vacuum tubes, one of which governs the extent to which said restoring means shall act and effecting operation of the disconnecting device, another of said tubes controlling the first tube as to its effecting the operation of the disconnecting device, said restoring means being effective upon disconnection of said actuator therefrom to reset the time controlled means.

9. The combination with a vehicle adapted to travel along a right of way, of means on said vehicle for affecting the progress thereof, means controlled by the distance traversed by said vehicle along the right of way, time controlled means associated therewith and governed thereby, an actuator therefor, a disconnecting device for said actuator, means for restoring the controlled means, a plurality of vacuum tubes, one of which governs the extent to which said restoring means shall act and effecting operation of the disconnecting device, another of said tubes controlling the first tube as to its effecting the operation of the disconnecting device, said restoring means being effective upon disconnection of said actuator therefrom to reset the time controlled means during part of its movement and the first mentioned vacuum tube acting when the normal condition of the tube is disturbed to prevent the restoring of the distance controlled means beyond a point where the time controlled means is not reset by further movement of the distance controlled means.

In testimony whereof we have signed this specification this 18th day of January, 1928.

THOMAS W. VARLEY.
WILLIAM C. NEIN.
